(57) **CLAIM**

The ornamental design for a display screen or portion thereof with graphical user interface as shown and described.

DESCRIPTION

FIG. 1 is a front view of a display screen or portion thereof with graphical user interface showing a first embodiment of our new design; and,

FIG. 2 is a front view of a display screen or portion thereof with graphical user interface showing a second embodiment of our new design.

The dot-dash broken lines illustrate a display screen or portion thereof and form no part of the claimed design. The even-dash broken lines illustrate portions of the graphical user interface that form no part thereof. The grayscale fill illustrates contrast which is part of the claimed design, and is not representative of any particular color.
